UNITED STATES PATENT OFFICE

RALPH C. HYDE, OF LOS ANGELES, CALIFORNIA, ASSIGNOR, BY MESNE ASSIGNMENTS, TO CLAUDE NEON ELECTRICAL PRODUCTS CORPORATION, LTD., OF WILMINGTON, DELAWARE, A CORPORATION OF DELAWARE

ELECTRODE FOR NEON TYPE OF LUMINOUS TUBES

Application filed July 6, 1929. Serial No. 376,351.

This invention relates to an improvement in the electrode utilized upon the neon type of luminous tubes. By the "neon type of luminous tubes" is meant to include all of those luminous tubes in which such gases as neon, argon, helium, etc. are employed.

In the neon type of luminous tube, the life of the tube is dependent in considerable part upon the extent of sputtering of the electrodes of the tube. It is customary to employ large electrodes or other equivalent means for reducing sputtering at the electrodes. However, it is found that in any such cases, a certain amount of sputtering occurs, which decreases the effective life of the tubes.

In the process of manufacturing the neon type of tubes, it is desirable that the electrodes of the tube be thoroughly processed for removal of occluded gases. This process generally requires that the electrodes of the tube be highly heated.

In order to prevent the temperature of the electrodes cracking the glass of the neon type tubes, a spacing means must be provided between the body of the electrodes and the tube.

It is the general object of the present invention to provide a neon type of luminous tube with an electrode in which the electrode includes a novel form of means for spacing the electrodes from the walls of the tube, which is of simple and economical construction.

It is a further object of the present invention to provide an electrode for a neon type of luminous tube, which electrode includes insulating means which will permit the electrode to approach more nearly the glass walls surrounding the electrode without danger of cracking the same.

It is a further object of the present invention to provide an electrode which will sputter less in operation and which will enable a neon type of luminous tube to possess a longer life.

It is a further object of the present invention to prevent the current from the electrodes of the neon tube from being drawn back against the sides of the electrodes and effect sputtering thereof.

Various further objects and advantages of

the present invention will be understood from the description of a preferred form or example of a neon tube and electrode therefor embodying the invention. For this purpose there is hereafter described, in connection with the accompanying drawings, a preferred form or example of a neon tube and electrode therefor embodying the invention.

In the drawings:

Figure 1 is an elevation of a neon type of luminous tube and electrode therefor, mainly in vertical section.

Figure 2 is a section on the line 2-2 of Figure 1.

Referring to the drawings, 2 indicates a glass tubing holding gas, preferably of the helium, argon and neon series and usually neon. The gas in the tube is preferably at 7 to 10 millimeters of pressure, although higher pressures may be employed. The glass tubing at its end, is enlarged somewhat, as indicated at 3, to form electrode chambers 4 housing the electrodes 5.

The electrodes 5 are preferably of metal in a solid state as distinguished from metal in a liquid state, such as copper, and in the particular form of the invention shown, are generally tubular in shape. The electrodes 5 are provided with lead wires 6 by which the tube may be energized from a suitable source of electrical potential, the wire being fused, as indicated at 7, in the ends of the glass tubing.

The electrodes 5 are of outside diameter but slightly smaller than the inside diameter of the enlargements of the glass tubing 2, which house the electrodes. Wrapped around the electrodes and disposed between the electrodes and walls of the glass tubing, are provided sheets of mica 8 or other equivalent insulating material. Sufficient turns of mica are provided between the electrode and inner walls of the glass surrounding the same as to substantially fill the intervening space. Preferably, the mica insulating sheet is extended, as indicated at 9, somewhat beyond the inner ends of the electrodes. It has been found, for reasons not at present fully comprehended, that the extension of the insulat-

ing wrapping around the electrode increases the life obtained from the luminous tube.

In practice the wrapping or covering of the electrode by a sheet of insulating mate-

5 rial, such as mica, which fills the intervening space between the metal electrode and the glass housing surrounding the same, operates to prevent the heat of the electrode cracking the surrounding glass housing.

10 Moreover, the wrapping of insulating material such as mica around the electrode is found to prevent the current being drawn back on the outer side of the electrode and thereby the wrapping operates materially to prevent sputtering of the electrodes. Neon tubes provided with the electrode herein described, on test have been found to possess over twice the life that the tube of the same type with other electrodes possess.

15 20 While the electrode herein described is well suited for carrying out the objects of this invention, it is to be understood that the invention is not limited to the particular form but includes all such modifications and 25 changes as come within the scope of the appended claims.

I claim:

1. In a gaseous discharge tube having an envelope enclosing a gas filling, an electrode 30 formed of solid material within said envelope, and a sheath of mica surrounding said electrode and interposed between said electrode and the adjacent walls of said envelope.

2. In a gaseous discharge tube having an 35 envelope enclosing a gas filling, an electrode formed of solid material within said envelope and having a substantially cylindrical exterior surface, a tubular sheath of mica covering the exterior of said electrode and interposed between said electrode and the adjacent walls of said envelope.

40 3. In a gaseous discharge tube having an envelope enclosing a gas filling, an electrode formed of solid material within said envelope, and having a cylindrical outer surface 45 of nearly the same external diameter as the internal diameter of said envelope, and a sheath of mica covering said electrode and substantially filling the space between said 50 electrode and said envelope.

4. In a gaseous discharge tube having an envelope enclosing a gas filling, an electrode 55 formed of solid material within said envelope, and having a cylindrical outer surface of nearly the same external diameter as the internal diameter of said envelope, and a wrapping of sheet mica covering the exterior surface of said electrode and substantially filling the space between said electrode and 60 said envelope.

5. In a gaseous discharge tube having an 65 envelope enclosing a gas filling, an electrode formed of solid material within said envelope, and a sheath of mica surrounding said 70 electrode and interposed between said elec-

trode and the adjacent walls of said envelope, said sheath of mica extending inwardly of said envelope beyond the inner end of said electrode.

6. In a gaseous discharge tube having an envelope enclosing a gas filling, an electrode 75 formed of solid material within said envelope and having a cylindrical outer surface of nearly the same external diameter as the internal diameter of said envelope, and a wrapping of sheet mica covering the exterior surface of said electrode and substantially filling the space between said electrode and said envelope, said wrapping of mica extending inwardly of said envelope beyond the 80 inner end of said electrode.

Signed at Los Angeles, California, this 28th day of June, 1929.
